UNITED STATES PATENT OFFICE

163,997

FISH LURE

Bernard James Gellings, Rosemary, Alberta,
Canada

Application November 4, 1949, Serial No. 5,866

Term of patent 14 years

(Cl. D31—4)

To all whom it may concern:

Be it known that I, Bernard James Gellings, a citizen of the Dominion of Canada, residing at Rosemary, in the Province of Alberta, Dominion of Canada, Rosemary, Alberta, Canada, have invented a new, original, and ornamental Design for a Fish Lure, of which the following is a specification, reference being had to the accompanying drawing, forming part thereof.

Fig. 1, is a plan view of a fish lure, showing my new design, and

Fig. 2, is a side elevational view.

The essential features of the design reside in the solid line portion.

I claim:

The ornamental design for a fish lure, as shown and described.

BERNARD JAMES GELLINGS.
